DISPLAY STRUCTURE

Albert J. Bates, Jr., Chicago, Ill.

Application November 22, 1934, Serial No. 754,261

16 Claims.

(Cl. 40—30)

This invention relates to improvements in display structures, and more particularly to action displays of the character utilized in store windows and similar show places to attract the attention 5 of pedestrians passing by, although the invention will have other uses and purposes as will be apparent to one skilled in the art.

In the art of advertising, it has become universally recognized that a display advertisement 10 in a store window or the like is considerably more effective if motivated or constructed so that one or more parts thereof is normally in motion. A movement quickly attracts the eye of a passer-by and once attracted the person will usually 15 linger sufficiently to ascertain the reason for the motion. If the display is of proper construction that length of time is quite ample to convey to the passer-by the nature of the article being advertised. However, heretofore action displays 20 have been prohibitively expensive for general and extensive usage. This expense is involved in the cost and labor of design and construction of the various parts of the display, the labor involved in building up the display, the installation and re- 25 movable, reinstallation and the general attention it requires. Obviously, an enormous financial expenditure is required for a single product to be advertised simultaneously in many different locations by means of action displays of the character 30 heretofore known.

With the foregoing in mind, it is an object of the present invention to provide action display structures so economical in character as to warrant very broad usage thereof.

It is a further object of this invention to provide a motive power unit, which may be standard 35 in character and adapted for installation in any of a plurality of action displays of different kinds and characters.

Also an object of this invention is the provision 40 of action display structures which may be readily assembled at the ultimate point where the display is to be provided, in a quick, easy manner, without the use of tools.

The invention also contemplates the use of a 45 substantially standardized motive power unit easily placeable in position, together with a plurality of cheap, die-cut members of cardboard or the like which may be readily assembled around a power unit to form an action display of a pre- 50 determined character, the power unit being of such design that it is adaptable to support and actuate substantially an unlimited number of types of displays.

Another feature of the invention is the provi- 55

sion of relatively cheap cardboard display units which may be assembled around a power unit to form an action display, the different members of the display varying in size and form at different points sufficiently to prevent the installation of 5 any member in any except the right position.

Another object of this invention is the provision 10 of suitable shaft construction for operating movable parts of an action display, such shaft construction being supportable in operating position by simple, cheap members of cardboard or similar material without any resultant binding of the shaft regardless of the warping of the cardboard members, and obviously there will be no 15 wear from operating parts upon the cardboard members.

The invention also contemplates the provision 20 of various members of cardboard and the like for assembling into an action display, the construction being such that the members are readily engageable one with the other without the use of tools and in a manner that will not materially detract from the front of the display.

Also an object of this invention is the provision 25 of a fabricated action display including shaft means arranged to be extended if so desired, and relatively cheap parts of sheet material which may be assembled in position to support the shaft means, counter-balance weights being provided where needed on moving parts of the display to 30 lessen the burden on the drive and shaft means.

Still a further object of this invention is to provide a fabricated display construction wherein the major portion of the display is fabricated 35 from a plurality of cheap members of sheet material, such members being used as fixed and as movable parts of the display and also as connecting rods for actuating the movable parts of the display, the construction being such that during operation there is a negligible amount of 40 wear upon the sheet material itself.

In accordance with the general features of this invention, a power unit has been provided incorporating both driving means, such as an electric motor, for example, and a basic or foundation structure for an action display. The power unit is preferably standardized so that a plurality of such units may be disposed at various locations, each unit being preferably identical in construction and size. The construction of the units is 50 such that each unit is adaptable to function as a driving means and basic supporting means of an action display of substantially any desirable kind, character or shape. Accordingly, a number of standardized permanent power units may be dis- 55

posed at any desirable points, for example, so many in one city, so many in another city, etc.

When it is desired to place a plurality of action displays in operation for advertising a certain product, the various action displays are formed preferably by die-cutting a plurality of cardboard pieces. Each of these pieces is so constructed as to prevent its being assembled in a display in any except the proper position. Novel shaft means are employed for driving the movable parts of the display, these shaft means being supported by the cardboard pieces. These pieces are used as frame members, connecting rods, movable display portions and general decorative pieces in accordance with the character of the display. The shaft means are so constructed as only to be mountable with the cardboard pieces of a particular display in one position. The shaft means may be disposed at any angle for vertical, horizontal or oblique driving, and may be very readily connected to the power unit. An entire display may be assembled around a power unit without the use of tools. The cardboard pieces used in the display are obviously very economical, and the time required to assemble the display and put the same into operation is practically negligible. In short, with the present invention an action display may be built up and put into operation at a substantially negligible increase in cost over a display in which all parts are stationary.

After a display has been in operation for the desired length of time, it is a very simple expedient to dismantle the display, and the various cardboard pieces may be placed into storage for future use at some subsequent date or destroyed. The power unit used in the display is kept at its central point or locality for subsequent use in an action display by the same or a different advertiser. It will be seen, therefore, that it is only necessary to fabricate the various cardboard parts of the display and ship these parts to the points where the displays are to be placed in operation, power units being already at these particular points, and with very simple directions accompanying the cardboard parts, the display may be assembled with a negligible amount of time at substantially any place at any time. With the flexibility of construction substantially unlimited and the relative parts so constructed as to permit an installation in only the right position, action display advertising of almost any character, design or shape can be had anywhere desired with great rapidity and at extremely low cost.

The present invention also has for an object the provision of a new method of assembling a display structure.

While some of the more salient features, characteristics and advantages of the present invention have been hereinabove pointed out, others will become apparent from the following disclosures.

The invention includes these and other features of construction and combinations of parts, and methods of assembly, preferred constructions of the invention being illustrated in the accompanying drawings, as more particularly indicated by the claims.

On the drawings:

Figure 1 is a front view of an action display structure embodying principles of the present invention.

Figure 2 is an enlarged side elevational view of the structure shown in Figure 1, with parts broken away and parts in section.

Figure 3 is a fragmentary rear elevational view of the structure shown in Figures 1 and 2.

Figure 4 is an enlarged top plan view of the power unit itself.

Figure 5 is an enlarged top plan sectional view taken substantially as indicated by the line V—V of Figure 2.

Figure 6 is an enlarged fragmentary isometric view of a portion of the construction taken substantially as indicated by the line VI—VI of Figure 2.

Figure 7 is another enlarged sectional isometric view taken substantially as indicated by the line VII—VII of Figure 2.

Figure 8 is an enlarged fragmentary plan sectional view, with parts in elevation, illustrating a form of shaft construction which may be utilized in the present invention, taken substantially as indicated by the line VIII—VIII of Figure 2, and showing portions of the shaft construction broken away and in section.

Figure 9 is a vertical sectional view through the shaft construction taken substantially as indicated by the line IX—IX of Figure 8.

Figure 10 is also a vertical sectional view through the shaft construction taken substantially as indicated by the line X—X of Figure 8.

Figure 11 is a vertical sectional view of the structure shown in Figure 10 taken substantially as indicated by the staggered section line XI—XI of Figure 10.

Figure 12 is a greatly enlarged part sectional, part elevational view of the pulley and shaft construction seen in the lower left hand corner of Figure 2.

Figure 13 is a further enlarged plan sectional view of the structure of Figure 12 taken substantially as indicated by the line XIII—XIII of Figure 12.

Figure 14 is a greatly enlarged vertical sectional view, with parts in elevation and parts omitted, of the shaft and crank arm construction seen in the lower left hand portion of Figures 2 and 5, taken substantially as indicated by the line XIV—XIV of Figure 5.

Figure 15 is a side elevational view similar to Figure 2 but illustrating a different type of display embodying principles of the present invention.

Figure 16 is a rear elevational view of the structure shown in Figure 15.

As shown on the drawings:

At the outset, it should be noted that where the term, "cardboard", is used herein and in the appended claims, this term is to be construed as meaning any suitable cheap and economical sheet material of similar character. Cardboard is highly desirable for use in connection with the present invention due to its ready cutting and adaptation, and various types of similar fibre and cellulose products could be used, as could wood fibre products or relatively thin sheets of wood or plywood.

The display in general

In the illustrated embodiment of the invention seen in Figures 1 to 14, inclusive, there is shown an action display including a forward shelf-like portion 1 above which projects a turn-table 2 carrying thereupon an article 3 to be displayed. Adjacent the turn-table a shaft 4 projects above the shelf and carries in the upper portion thereof a rectangular member 5 oscillatable back and forth between open and closed positions in the manner of a cover of a book. Preferably integral

with the shelf 1 is an upright panel 6 and behind this panel is an oscillatable panel 7 divided in the upper portion thereof into two laterally extending parts 8 and 9, respectively, by means of a division notch 10, as seen more clearly in Figure 3. 5 Adjacent the lower end thereof, the panel 7 carries a counter-weighted neck portion 11 to lessen the load on the power means which oscillates the panel. With reference to Figures 1 and 3, it will 10 be seen that when the side portion 8 of the panel 7 is exposed laterally of the panel 6, the side portion 9 is immediately behind the panel 6 and so is invisible from the front of the display. Upon 15 the next oscillatory movement of the panel 7, the side portion 9 comes into view and the side portion 8 is hidden behind the panel 6.

Behind the oscillatable panel 7 is a relatively large fixed panel 12 which appears as the back of the entire display. This panel 12 has an arcuate 20 opening 13 in the upper portion thereof (Figure 1), through which reading matter 14 carried by a disc 15 is visible. The disc 15 is mounted for rotation behind the panel 12. It will be seen, therefore, that the display in general includes 25 six panels having considerable surface upon which any suitable advertising may be placed, as well as four separate moving parts. The complete stand incorporates four different motions, namely, oscillation in a vertical plane, oscillation in a 30 horizontal plane, rotation in a vertical plane and rotation in a horizontal plane. It is also to be understood that the sign may include as many moving elements as may be desired and these motions may be of the character shown or may be 35 disposed obliquely, the kinds of movement and the direction thereof being substantially unlimited.

The standardized power unit and foundation structure

40 In the use of the present invention, the power units, of which one is preferably used for each display, are preferably as nearly identical as possible. In other words, each unit is of the same 45 size, the housing is of the same general size and contour, and the upright foundation supports are also preferably of the same size and disposed in identical manner in each unit.

It is to be understood that while I have, in the 50 illustrated embodiments of my invention selected a type of display which requires the use of only one of my novel power or motor units, it is fully contemplated that in other or more complex types of displays two or more of these units may 55 be associated together to provide for the desired movements. Also, it should be noted that I have attained best results by using a power unit which is so geared that both crank and rotatable drive elements connected thereto operate at a speed 60 not to exceed 30 R. P. M. or a relatively low one.

The power unit is best seen in Figures 2 and 4. The unit comprises a suitable form of housing 65, and in this instance the housing is shown as being substantially trapezoidal in horizontal cross-section. As indicated by dotted lines in 70 Figure 2, the housing contains a suitable driving element, in this instance an electric motor 17, including a speed reducer, which may be for alternating current, direct current or the universal type. The shaft 18 of the motor projects without 75 the housing, and upon the end of this shaft a multi-step pulley 19 is mounted. This pulley carries a crank arm 20 projecting therefrom upon the outer end of which is a thumb nut and bolt connection 21 for attachment to the crank arm

of a connecting rod. A vertical shaft 22 (Figure 2) is also disposed within the housing and projects without the housing to support a horizontally disposed multi-step pulley 23 also equipped with a crank arm 24 suitably apertured to accommodate a thumb nut and bolt connection for a connecting rod. The shaft 22 is connected with the motor shaft 18 in any suitable manner, such as by a worm gear and pinion. It is to be noted that it is not essential that the pulley 23 be 10 mounted immediately adjacent the pulley 19, but may, if so desired, be disposed at the opposite end of the housing and geared to the opposite end of the motor shaft. Current may be supplied to the motor by inserting a standard form of plug in a 15 receptacle 25 disposed on one of the side faces of the housing.

To provide a foundation or basic structure for the display, a plurality of uprights 26, in this instance four, preferably of metal, are associated 20 with the motor housing. The uprights preferably extend to the top of the housing 16 which is suitably apertured to accommodate them and rest upon the floor of the housing, the uprights being held in position by means of transverse 25 rods 27 projecting through the uprights in the side walls of the housing. As seen best in Figure 6, the uprights 26 may each be provided with a plurality of spaced apertures 28 to afford means 30 of connection for display apparatus at substantially any desired location along the uprights.

It is to be especially noted that the uprights 26 are disposed in such locations and at such angles that a member shaped for connection to a particular pair of uprights will connect with 35 that pair only and will also connect with that particular pair in only one position, in the event the top side of the member is kept uppermost during the assembly. In this particular instance, each of the uprights are rectangular in cross-section and have the rear portion thereof disposed inwardly further than the forward portion. In addition, the distance between the rearmost pair of uprights is less than the distance between the forward pair of uprights. By disposing the uprights in this or in an equivalent manner, the device is rendered fool-proof in that, during the assembly of the display, the various parts to be connected to the upright can only be connected thereto in the correct way. Standardized power 40 units of the character set forth herein, each including a housing, a power element therein, suitable pulleys, and uprights forming a foundation structure for the display, may be provided in various central locations in any desirable quantity 45 and kept in these locations. When it is desired to provide advertising displays of any character, it is a simple expedient to manufacture various cardboard parts for the displays, ship these parts to the points of exhibition, and assemble them 50 around a power unit already located near to the place of exhibition.

If so desired, illumination may be provided for certain portions of the signs by means of an electric lamp 29 connected through a suitable 65 lead 30 to a socket 31 also associated with the motor housing and, as indicated at 32 in Figure 2, any suitable form of make and break contact equipment may be provided to cause periodic illumination of the lamp. This equipment 32 is 70 connected to the socket 31 by means of suitable cable conductors 33.

The frame and panel construction

As stated hereinabove, the frame members and 75

panels are preferably made of cardboard or similar material. These frame members and panels are sufficient in their association with the power unit and the uprights 26 to support the display in operative position.

To provide initial easy assembly for the display structure, the lowermost or positioning panel 34 is provided. This panel has a substantially trapezoidal rear portion suitably apertured to accommodate the motor housing 16 which, as above explained, will fit in the aperture in the panel 34 in only one position. The panel 34 terminates at its rear end in a downwardly turned foot 35 (Figures 2, 3, and 5), which maintains the panel elevated above the floor or the surface upon which the motor housing 16 may rest. Adjacent the largest upright panel 12, the panel 34 is set inwardly along its lateral edges, as indicated at 36 in Figure 5. Adjacent this set-in portion, the panel 34 terminates except for the central part thereof which extends forwardly and is folded upwardly at the forward part, as indicated at 38 in Figures 2 and 3, and then folded rearwardly to form a portion 39 which rests on top of the motor housing 16. As indicated at 37 in Figures 2 and 5, a downwardly turned foot is struck from the lower central portion of this panel to maintain the entire panel substantially level in its height from the floor. Of course, when the structure is initially assembled, the entire panel unit 34 and the motor housing are preferably united first.

The forwardmost or shelf panel 1 has an undeturned portion 40 (Figures 2 and 5), which is apertured or recessed sufficiently to accommodate the leg or foot 37 on the upright portion 38 of the panel 34. The upper portion of this panel is turned rearwardly to form a shelf 41 from which the side portions extend rearwardly beyond the shelf 41 and each terminates in a tongue 42 (Figure 3), projecting through a suitable aperture in the largest upright panel 12. Immediately below the horizontal part of the shelf 41, the panel 12 is provided with integral forwardly extending portions 43 inset from the sides of the panel and extending forwardly to the vertical portion 1 of the shelf (Figure 5). The central portion of the shelf 41 bends upwardly into the upright panel 6 of which the upper end is turned rearwardly as at 44 and projects through a suitable aperture in the panel 12, as indicated at 45 in Figure 2. This structure so far described is maintained in substantially rigid position by the various interlocking connections and aided by means of a pair of side wings 46 preferably integral with the panel 12 and extending from above the panel 6 clear to the floor.

As seen best in Figures 2 and 3, the upper part of the panel 12 extends rearwardly and downwardly, as indicated at 47. The part 47 is provided with a relatively large aperture 47a to accommodate a projecting portion 48 of a channel-shaped frame member 49. The projecting portion 48 is somewhat wider than the aperture 47a and is notched on each side as at 48a to interlock with the edge of the cardboard adjacent the aperture. Of course, it may be more feasible to bend the sides of the channel inwardly, place the projection 48 through the aperture, and then straighten the channel sides into engaging position. It will also be noted that, if so desired, pins may be inserted through the projection, and all of the tongue and slot connections, including the various panel and frame members in setting

up the display structure, may be retained in either of these or an equivalent manner.

The channel frame member 49 embraces the forward pair of foundation supports or uprights 26 and is attached thereto by means of a substantially horizontally disposed flange 50 struck directly from the frame member, as best seen in Figure 6. The flange 50 is provided with suitable apertures for receiving the uprights 26, and in view of the peculiar angle of the uprights 26, the frame member 49 can only be placed in position in the proper way. A pin 51 may be transversely disposed through the aperture 28 in each upright 26 immediately above the flange 50 to maintain the frame member 49 in position. The lower end of the frame member 49 is also provided with a flange 52 slipped downwardly over the uprights 26 and also pinned in position. This flange 52 rests upon the upper portion 39 of the positioning panel 34 and holds this portion 39 upon the motor housing 16, thereby giving a sufficiently rigid construction.

In similar manner, a second and shorter channel frame member 53 is connected to the rearmost pair of foundation supports or uprights 26. Both channel frame members 49 and 53 are readily attachable in position, and these members are preferably mounted so that the channels thereof confront each other, or the two members 49 and 53 may be one piece.

It will also be noted that in some cases it may not be feasible or desirable to have the frame members 49 and 53 resting upon the top portion 39 of the positioning panel 34 and it is obvious that if such is the case, the right angular flanges 55 of these frame members may be disposed in any desirable location along the uprights 26, and pins 51 inserted in the apertures 28 immediately below the lowermost flanges 52 to hold the frame members in position. It will also be observed that the flanges 50 aid considerably in stiffening the frame member.

Suitable means for supporting the lamp 28 may be provided by simply gluing or otherwise attaching a relatively small panel member 54 to one side of the laterally extending portion of the panel 12 below the shelf 41, as best seen in Figure 5. A socket for the lamp may be mounted in this panel 54 in an obvious manner.

Vertical shaft construction and mounting

In the present instance, for the proper operation of the turn-table 2 carrying the display element 3 and the shaft 4 carrying the laterally oscillatable display element 5, vertically disposed shafting is necessary together with means for connecting the shafting to the power unit. The construction of the vertical shaft means in this instance has been so adapted that all of the mechanical parts may be assembled in operative position prior to installation in the front display structure. In other words, it is not necessary to assemble the entire shafting at the same time it is installed in position in the frame and panel members, but certain of this shafting may be preassembled and merely dropped or placed in position.

As best seen in Figures 2, 12, and 13, the shaft construction for the turn-table 2 includes an outer rigid sleeve 55 which may be made of any suitable material, a phenolic or alcoholic condensation product functioning nicely for this purpose. This tube 55 together with its contents is merely dropped through a suitable aperture in the upper portion 39 and the lower portion of

the positioning panel 34. In most cases, no locking device or anchoring means are necessary, the lower end of the tube merely resting upon the floor. Mounted for rotation within the 5 tube 55 is a somewhat shorter tube 56 which is preferably made of brass or some similar economical tubing. The tube 56 is journaled within the tube 55, and a multi-step pulley 57 is fixedly secured to the upper end of the tube 56 for 10 rotation therewith. The pulley 57 is securely keyed to the tube 56, and a suitable plug 59 may be pinned in the lower end of the tube 55 to function as a base support for the lower end of the shaft 61 and the tube 56.

15 The upper end of the tube 56 is preferably deformed as at 60 to fit around a shaft 61 which is polygonal in cross section, whereby the shaft 61 will be rotated with the tube 56. The shaft 61 extends through a suitable aperture in the 20 shelf 41 and has fixedly connected thereto a suitable flanged collar member 62 which carries the turn-table 2. This shaft 61 is preferably an inexpensive rod or polygonal wire, and in assembling this shaft construction, it is a simple expedient to vary the length of the shaft 61 by merely snipping off the polygonal wire at the desired length. Since the wire fits within the deformed portion of the hollow shaft, it will be seen that it is very simple to provide a shaft 61 25 of any desirable length.

30 The operation of the turn-table 2 may be effected by connecting a belt 63 around the pulley 57 and also around the pulley 23 of the power unit. This belt is preferably merely a piece of string wrapped around the respective pulleys and tied in a suitable knot, the knot not interfering with the operation. The belt 63 (Figure 5) passes through a suitable aperture 64 in the frame member 49 and a similar aperture is also provided in the other channel frame member 53. Of course, the speed of the turn-table may be adjusted as desired by merely connecting the belt 63 to the proper step on the pulleys 57 and 23, these pulleys being in inverse relationship to each 45 other.

40 The laterally oscillatable display element 5 is in this case mounted directly and fixedly upon the rod 4 which is also polygonal in cross-section. A shelf construction may be associated with this 50 element 5 that is somewhat similar to that associated with the turn-table 2.

55 In this instance, a tubular casing member 65 is utilized which may be identical in construction and mounting with the tube 55. Within the tube 65 is a hollow shaft 66, and fixedly secured to the upper end of this shaft so as to rotate therewith is a plate member 67 (Figures 5 and 14). This plate member has a depending collar 68 which seats upon the even cut upper end of the tube 66. A crank arm 69 having an aperture of the same polygonal shape as the shaft 4 is seated over the shaft 4 on the plate 67 and connected to the plate 67 by means of a thumb nut and bolt connection 70. This connection is made through 65 a slot 71 in the plate 67 so that the termination point of oscillation of the display element 5 may be adjusted as desired.

70 Formed preferably integral with the plate 67 is a crank arm 72 extending substantially oppositely to the slot 71. This crank arm is provided with a plurality of spaced apertures 73 therein permitting attachment of a connecting rod 74 to the crank arm at a suitable point so that the degree of oscillation may be adjusted therealong 75 consistent with the desired operation of the ele-

ment 5. Connection is made by means of a suitable thumb nut and bolt attachment.

The connecting rod 74 is also preferably made of cardboard and predesigned in the right length and carrying suitable indicia designating 5 through which of the apertures 73 connection is to be made for the particular display at hand. The opposite end of the connecting rod 74 is attached by means of a thumb nut and bolt connection to the crank arm 24 associated with the 10 pulley 23 (Figure 2). The connecting rod is preferably folded into channel form to increase its strength, and this connecting rod may be stamped out of cardboard together with the panel and frame members. Any suitable form of arrangement in the thumb nut and bolt connection at the ends of the connecting rod may be used to lessen the wear on the connecting rod. The drive of the display element 5 will be obvious from the foregoing. The connecting rod 74 will function 20 as a pitman, one end of the rod rotating with the rotation of the pulley 23, and the other end of the connecting rod causing an oscillation of the crank arm 72 which in turn results in a lateral oscillation of the display element 5 through 25 the polygonal shaft 4. It will be noted that a disc and oscillating shelf might also be used on the shaft 4.

Horizontal and oblique shaft construction including extension elements and attaching plates 30

In the present instance, for the particular display structure illustrated, two horizontal shaft constructions are necessary, one for operating the oscillatable member 7, and one for operating 35 the rotatable disc 15. As these shaft constructions are substantially the same in character, it is only necessary to describe one of them herein with specific reference to the details of construction.

40 While the shaft constructions for the oscillatable element 7 and the disc 15 are both disposed horizontally in the present instance, it will be apparent from the description hereinafter that such shaft constructions may be mounted in 45 oblique positions, if so desired, with obvious variations in the hubs or bushings in the outer sleeve of the shaft for connection with the frame and panel members.

45 With reference more particularly to Figure 8, 50 it will be seen that a shaft 75 is utilized for operating the oscillatable element 7. In this instance, the shaft 75 is shown in two parts to illustrate how a shaft may be extended in the event the shaft is not sufficiently long for the particular 55 display desired. For the purpose of clarity, the part nearest the power unit is designated 75 and the other part which is connected to the oscillatable display element 7 is designated 75a.

The shaft part 75 is rotatable within a tube 60 76 of brass or some similar economical metal to form a bearing surface for the shaft. The tube 76 in turn may be fixed within a tube 77 of any desirable material, such, for example, as fiber. At spaced intervals therealong, this tube 77 is provided with flanged hubs or bushings for engagement with the respective frame and panel members of the display structure. There is preferably 65 the same number of bushings as there are frame and panel members, in this instance one extra bushing being shown to illustrate the flexibility of the construction, this added bushing being ready in the event the same shafting construction is used in a display structure incorporating an added frame or panel member.

In this instance, the tube 11 on the shaft 75 is provided with three flanged bushings or hubs 78, 79, and 80, respectively, the bushings preferably being formed integral with the tube 11. These bushings are seated in slots or recesses in the frame and panel members with the flanges of the bushings embracing the respective frame and panel members to support the shafting construction in operative position.

For example, the frame member 53 is provided with an aperture 81 (Figure 3) terminating at its lower end in a slot 82 in which the central part of the bushing 78 is seated. To hold the shafting construction in proper position, a spring or hook element 83 is provided, this element having one end secured around the tube 11 adjacent the bushing 78, and the other end terminating in a somewhat rearwardly bent hook 84 designed for resilient engagement in an aperture 85, preferably 20 of triangular shape with an apex disposed upwardly, through the panel member 53 at the proper distance below the slot 82. Thus, the shafting construction is held firmly in position. The construction just described may be seen 25 clearly in Figure 7, which illustrates the mounting of the shafting for connection with the rotatable disc 15. All of the bushings utilized in horizontal shafting construction with the display structure herein shown are preferably held in 30 position in substantially the same manner.

With reference to Figure 2, it will be seen that the frame member 49 is also provided with an aperture 86 terminating in a similar slot for the reception of the bushing 79 which is held in position in similar manner by a spring element 83. The bushing 80, seen in Figure 8, is not utilized with any frame or panel member in the present construction, but may be utilized in like manner in the event another panel or frame member is 40 incorporated.

The shaft extension portion 75a is joined in a similar brass tube fixed within an external tube 11a of the same character as the tube 11. The tube 11a is provided with a bushing 87 engaged 45 in like manner in a suitable slot in the panel 12, security being had by means of a spring clip.

The shaft portion 75a is connected to the oscillatable display element 7 by means of a connection construction to be later described and 50 generally indicated by reference numeral 90 in Figure 2. The two shaft portions 75a and 75 are connected together by a suitable form of clutch, generally indicated by reference numeral 91, and it will be noted that the aperture 88 in the panel 55 12 is of sufficient size to permit the passage therethrough of the clutch 91 prior to the seating of the flanged bushing 87 in its respective slot. The rear end of the shaft 75 has attached thereto a crank arm 92 (Figures 2, 3, and 8) provided with 60 a plurality of spaced apertures in substantially the same manner as the crank arm 72 hereinabove mentioned to provide a selective attachment for a connecting rod to permit preselection of the proper stroke of the crank arm for the 65 proper oscillation of the display element. It will be noted that the apertures 86 in the frame member 49, and 81 in the frame member 53 are of sufficient size to permit the passage therethrough of the crank arm 92 prior to the disposition of 70 the flanged bushings 78 and 79 in their respective slots.

At this point, it should be clearly noted that the flanged bushings 78, 79, 80, and 87 are preferably each of a different size, and the slots in the 75 respective frame and panel members 12, 49, and

53 are each sized for a particular bushing. Such construction provides for very quick assembly of the display structure with the elimination of error in the placing of the respective parts, i. e., it is impossible to mount the shafting construction in 5 any but the correct position.

The crank arm 92 is attached to the end of the shaft 75 by means of a suitable collar 93 keyed to the shaft 75. A connecting rod 94, preferably 10 of the same construction as the connecting rod 14, is attached to the crank arm 29 on the pulley 19 of the motor shaft by means of the thumb nut and bolt connection 21 above referred to, and the opposite end of this connecting rod is attached in similar manner to the crank arm 92 at the 15 proper aperture for the desired oscillation. The aforesaid panel-weighted neck 11 upon the display element 7 aids in lessening the load on the motor 17 of the power unit during oscillation of the element 7. 20

The attachment connection 90 between the end of the shaft portion 75a and the oscillatable element 7 is best seen in Figures 8, 10, and 11. Glued or otherwise attached to the reverse side 25 of the oscillatable member 7 is another element 96 of cardboard or similar material and having the general shape of a disc with a sector cut off the lower portion. This member is provided with a recess 97 therein having somewhat straight side walls and an arcuate top. Another member 98 30 of similar shape is glued to the member 96 and is provided with a recess 99 of similar shape to the recess 97 but of a smaller size, thereby making substantially a pocket defined by the recess 97 between the member 98 and the oscillatable member 7. 35

Within the pocket so formed is an envelope 100 preferably formed by metal and closed along the bottom edge. As best seen in Figure 11, a collar 101 is keyed to the shaft 75a. An aperture is 40 provided in the rear side of the envelope 100 of sufficient size to permit the free rotation of the collar therein. The collar 101 is formed in the shape of a rivet, as indicated at 103, to hold securely in position an operating plate 104 which 45 oscillates with the shaft and collar. The other side of the envelope 100 is provided with an aperture of just sufficient size to receive the projecting end of the shaft 75a and afford journal means for this end of the shaft. The operating plate 50 104 is provided with a tongue 105 extending therefrom into an offset recess 106 in the member 96, the recess being sufficiently large to provide ample 55 delay or lost motion to permit an observer to read the advertising upon the exposed side 8 or 9 of the element 7 before the other side is brought into view. To aid in keeping the parts in assembled 60 position, a bendable tab 107 projecting preferably integrally from the disc-like member 98 extends across the aperture 99 into contact with the collar 65 101. With the various shaft parts previously assembled, it is a simple expedient to fold back the tab 107 and insert the end of the shaft together with the envelope 100 and the operating plate 70 104 in the pocket 97 behind the inner edge of the member 98 and permitting the tab 107 to be restored to its normal position by folding it back. 75

With the connection just above described, the operation of the oscillating display element 7 is 70 extremely simple. Assuming that the parts are in the position seen in Figure 10, the portion 9 will be visible, and as the shaft 75a is turned to the right by means of the connecting rod 94, the portion 9 will remain in exposed position until the tongue 105 strikes the opposite wall of the 75

recess 106, when the element 7 will be moved so as to conceal the portion 9 and expose the portion 8. The opposite is true upon the return stroke of the connecting rod.

5 It will be noted here that if the recess 106 is the same size as the tongue 105, then no slip will be provided for.

The clutch 91, which is used to join the shaft extension 75a to the main part of the shaft 75, 10 is best seen in Figures 8 and 9. The clutch end of the shaft portion 75a is provided with a keyed collar 108 to which is attached a plate 110. This plate 110 may be of any preselected shape, in this 15 instance being shown as substantially hexagonal with one portion removed along the line 111 in Figure 9 to make the plate seven sided, as indicated by the full lines in Figure 9. Another plate 112 of a different irregular shape is similarly attached to the adjacent end of the shaft 75. The 20 shape of the plate 112 in this instance is indicated by the dotted lines in Figure 9 except for that portion of the plate extending beyond the cut-out portion of the plate 110. Each of these plates is preferably notched in a plurality of 25 spaced locations, in this instance three, as indicated at 113. A pin bolt 114 may be readily placed in each of the notches, each pin bolt having an enlarged rear portion engaged against the plate 110 and a narrow threaded portion extending 30 through the notch, the bolt being held in position by means of a thumb nut 115 placed against the surface of the plate 112. These bolts 114 are preferably held together by means of a wire 116 passing through the enlarged ends of the bolts, 35 thus preventing loss of the bolts and permitting very quick connection of the plates.

The peculiar shapes of the plates upon the ends of the shaft extension utilized in the display structure preferably differ so that they cannot be 40 assembled incorrectly. Insofar as the clutch of the character 91 is concerned, it is a simple expedient to place the flat faces of the plates together and secure them in position. However, each of the plates upon the shaft may be utilized 45 for a connection such as the attachment connection 90, to a movable portion of the display, the irregularity in the shapes of the plates preventing attachment of that particular shaft to the wrong display element.

50 The connection of the respective plates to each shaft length may be of the same character as illustrated and above described in connection with Figure 11.

From the above shafting construction, it will 55 be apparent that the structure may be assembled very expeditiously and without the use of tools. It will also be apparent that in the event a central portion of a movable display element is exposed to the eye, the outside face of this element will 60 not in any manner be defaced by means of the connection to a shaft.

With reference now to Figure 2, it will be seen 65 that a similar shaft construction is provided for operation of the rotatable disc 15. In this instance, no extension length of shafting is necessary. The shaft construction is the same as that previously described in connection with the operation of the oscillatable element 7, including a shaft 75b journaled in a metallic tube 76b, in 70 turn fixed within an external tube 77b. The tube 77b is provided with a pair of flanged hubs 117 and 118 for engagement in suitable slots in the frame members 49 and 53, respectively, (Figures 2 and 7). As seen best in Figure 7, the panel 53 75 is provided with a slot 119 in the upper end

thereof for reception of the flanged bushing 118, and the bushing is held in position by means of a spring clip 120 having a hook 121 projecting through an aperture 122 disposed at a proper distance below the slot 119.

The frame member 49 must of necessity be provided with an aperture 123 above the slot for the hub 117, and this aperture is preferably made sufficiently large to permit the passage therethrough of a stepped pulley 124 secured to the 10 rear end of the shaft (Figures 2 and 3). The other end of the shaft is connected to the rotatable disc 15 by means of an attachment connection 90a which is of the same character as the attachment connection 90 above described. 15

The flanged hub 117 is held in position in the same manner as is the hub 118, but each of these hubs, together with their respective slots in the frame members 49 and 53, are preferably of different size to eliminate error in the mounting 20 of the shaft. The plate upon the end of the shaft used in the attachment connection 90a is also preferably of a different shape than the plate used in the attachment connection 90 for the same reason. 25

A belt 125 establishes driving connection between the pulley 19 upon the motor shaft and the pulley 124, this belt also being preferably merely a piece of string with the ends tied together.

In view of the above description, it will be apparent that the shafting construction utilized in the present display structure is of such character that although mounted in frame and panel members of cardboard or similar sheet material, there can be no binding of the shafts themselves due to 35 warping or misalignment of the frames and panels, since each shaft is journaled within a rigid sleeve.

The formation of a display of different character

In Figures 15 and 16 I have illustrated how the present invention may be utilized to provide a display of a different character. In this instance, only two movements are utilized in the display, an oscillatory movement in a vertical plane and a 45 rotary movement in a vertical plane.

In this instance, the same power unit is, of course, utilized, but nothing will be connected to the pulley 23 on top of the housing 16 because there is no movement in a horizontal plane in the 50 present display structure.

In this instance, the display proper includes a front panel 126 of the general contour of a man, before which an arm 127 is oscillatable. Behind the panel 126 is a rotatable disc 128, a portion 55 of which is visible from the front of the display, and behind the disc are a pair of spaced frame members 129 and 130 secured to the forward pair of uprights 26 and the rear pair of uprights 26, respectively. The frame members are substantially trapezoidal in shape with the lower ends thereof resting upon the housing 16 of the power unit. A positioning panel 131 having a bent flange 132 in the forward end thereof glued or otherwise secured to the panel 126 is disposed 60 in a position slightly oblique from the horizontal. This positioning panel is suitably apertured to accommodate the motor housing 16, although, if so desired, the positioning panel may be provided with flanges for the reception of the motor 65 housing.

The frame members 129 and 130 are connected with the respective pairs of uprights 26 in the manner previously described in connection with the frame members 49 and 53. 75

A shaft construction substantially identical with that shown in Figure 8 is utilized for the oscillation of the arm 127. This shaft construction is provided with flanged hubs 134 and 135 for engagement in lateral slots 136 in the frame members 129 and 130, respectively. In each instance, the flanged hub is held in position by means of a spring clip 137 engaged in a suitable aperture 138 spaced inwardly from the termination 10 of the slot. As is the case with the previously described construction, the flanged hubs and their respective slots are preferably of different sizes to prevent error in assembling. Extension shafting is provided and held in place by means of a 15 clutch construction 91a of the same character as the aforesaid clutch 91, and the extension shafting is connected to the arm 127 by means of an attachment connection 99b of the same character as the attachment connections 99 described above. 20 Oscillation of the arm is provided by means of a crank arm 139 attached to an end of the shafting construction and connected to the crank arm 20 on the pulley 19 of the motor shaft 18 by means of a connecting rod 140. This construction is 25 substantially like that previously described in connection with the oscillation of the display element 7. It will be noted that the connecting arm 140 in this case is considerably longer than the connecting arm 94.

30 Another shafting construction, generally indicated as 141, is similarly mounted in the frame members 129 and 130 adjacent the opposite sides thereof. This shafting is connected by means of an attachment connection 99c with the rotatable 35 disc 128. At the other end thereof the shafting construction carries a stepped pulley 142 connected by a belt 143 to the pulley 19 on the motor shaft.

The flexibility of the parts permits their connection in such a manner that proper timing 40 results between the rotation of the disc 128 and the up and down oscillation of the arm 127 in keeping with the particular advertising upon the display structure. The construction and mounting of the various parts are substantially the same 45 as that previously described in connection with Figures 1 to 14, inclusive, and it will be noted in many instances that the mechanical parts (or parts other than the cardboard ones) may be used without change therein in a display of either of the characters illustrated.

50 From the foregoing, it will be apparent that I have provided novel display structures capable of quick and easy assembly in substantially any location, including the equipment to provide movement of the display of substantially any desired character or nature, the invention being sufficiently durable for the purposes intended and fool-proof in character so that it cannot be assembled in any but the correct way. Further, 55 it will be noted that with the extremely economical material used, with the possible exception of the basic power unit, and the economical manner in which the relative parts may be assembled, action displays may be provided at approximately the same cost as stationary displays. Further, the flexibility of the invention permits ready adaptation of the operating parts for displays ranging to an extremely wide variation in 60 form and character. In addition, it will be noted that the present invention includes a novel method of assembly in advertising displays, which method is deemed to be sufficiently clear from the 65 foregoing as to warrant no further description.

I claim as my invention:

1. A driving unit for an action display device, including a housing, a driving element supported by said housing and equipped with means for connection to movable elements to be driven, and a plurality of polygonal uprights rising from said housing for receiving thereover apertured display pieces, said uprights being disposed at such angularity relatively to each other that a piece apertured for two uprights can only be associated with a certain two and with those only in one way. 10

2. A driving unit for an action display device, including a housing, a driving element supported by said housing and equipped with means for connection to movable elements to be driven, and a plurality of polygonal uprights rising from said housing for receiving thereover apertured display pieces, said uprights being arranged in irregular polygonal order to prevent the application of a display piece in any but the correct place. 20

3. A driving unit for an action display device, including a housing, a driving element supported by said housing and equipped with means for connection to movable elements to be driven, a plurality of polygonal uprights rising from said housing for receiving thereover apertured display pieces, said uprights being disposed at such angularity relatively to each other that a piece apertured for two uprights can only be associated with a certain two and with those only in one way, and means selectively associated with said uprights to effect a support for display pieces at various points along said uprights. 30

4. In an action display, a power unit including driving means and spaced upright supports of irregular disposition, a plurality of decorated advertising members visible from the front of the display, a plurality of supporting and adapting parts for engagement with said advertising members and said uprights, said parts being formed of substantially the same material as said advertising members and irregularly shaped for connection with said members and said uprights in only one position. 40

5. In an action display, a driving unit including polygonal uprights in irregular disposition, supporting members for association with said uprights, each of said members having apertures for receiving certain of said uprights, said apertures being so disposed and shaped that each member can be associated with the respective uprights in only one position, and movable advertising members associated with said supporting members and connected with said driving unit. 45

6. A fabricated action display including a plurality of decorated advertising members certain of which are movable, a plurality of stationary supporting members, and a plurality of differently shaped clutch elements, all made of cardboard, shaftings mountable on said supporting members, 60 each shafting carrying one of said clutch elements, and each movable advertising member having one of said clutch elements secured thereto complementary to only one of those carried by said shaftings. 65

7. In combination in a fabricated action display, a standard power unit including a plurality of spaced uprights, a pair of supporting panels attachable to said uprights in spaced relationship, a shaft assembly carrying bushings of different sizes, and said panels each having an opening 70 therein of a size to fit only a different one of said bushings. 75

8. In combination in a fabricated action display, a standard power unit including a plurality 75

- of spaced uprights, a pair of supporting panels attachable to said uprights in spaced relationship, a shaft assembly carrying bushings of different sizes, and said panels each having an opening therein of a size to fit only a different one of said bushings, said panels each having another opening therein adjacent said first opening, and an anchoring element carried by the respective bushing lockably engageable in said other opening. 5
9. In a fabricated action display, a shafting assembly having a pair of differently sized bushings, and a pair of cardboard panels each having a slot therein for the reception of one of said bushings, said slots being of different sizes in keeping with the bushings whereby said shafting assembly can be mounted on said panels in only one position. 10
10. In an action display, a pair of spaced cardboard supports each having a different sized opening therein, and a shaft assembly including a shaft, suitable bearing means surrounding said shaft, and bushings carried by said bearing means each sized to fit in a different one of said openings. 15
11. In combination in a fabricated display structure, a supporting unit including a plurality of uprights arranged irregularly, and supporting panels for association with said uprights, each of said panels having a member secured thereto, 20 said members being scored for bending and the part defined by the score apertured to fit over only a certain pair of said uprights. 25
12. In an action display of the fabricated type for assembly on location, an advertising piece to be motivated, shaft means for driving said piece, and clutch means for connecting said shaft means and said piece including a cardboard member having an irregularly shaped socket therein with a flap thereover, and a member shaped to fit said 30 socket and be retained therein by said flap, one of said members being attached to each of said shaft means and said piece. 40
13. In a fabricated action display adapted for ready assembly, a plurality of movable advertising pieces, a shaft for driving each piece, and a clutch between each piece and its respective shaft, said clutches each comprising a socket member of cardboard with a flap extending over the socket, 5 and a member shaped to fit said socket and be retained therein by said flap, said clutches being so shaped that only one of said members will fit any one of said socket members. 15
14. In an action display of the fabricated type adapted for ready assembly on location, an advertising piece to be motivated, a shaft for driving the same, a clutch made of cardboard for connecting said piece and said shaft, including a socket member having an offset in the socket 15 thereof and a resilient flap overlying the socket, and a member seatable in said socket behind said resilient flap and having a projection extending into said offset to establish a driving connection. 20
15. In an action display of the fabricated type adapted for ready assembly on location, an advertising piece to be motivated, a shaft for driving the same, a clutch made of cardboard for connecting said piece and said shaft, including a socket member having an offset in the socket 25 thereof and a resilient flap overlying the socket, and a member seatable in said socket behind said resilient flap and having a projection extending into said offset to establish a driving connection, 30 said projection being of less size than said offset to provide a lost motion drive for said advertising piece. 40
16. In a fabricated action display for assembly about a standard power unit, a pair of movable exhibitory members, a pair of drive shaftings to 35 actuate said members, supporting means to carry said shaftings, a cardboard driven clutch member secured to the back of each exhibitory member, and a similar driving clutch member carried by each said shafting, each said driving clutch member being so shaped as to engage only one of said driven clutch members and not the other. 40

ALBERT J. BATES, JR.
